UNITED STATES PATENT OFFICE.

MEYER ROSEN, OF BLOOMINGTON, ILLINOIS.

SELF-LOWERING JOURNAL-JACK.

1,276,574.

Specification of Letters Patent. Patented Aug. 20, 1918.

Application filed October 10, 1917. Serial No. 195,699.

To all whom it may concern:

Be it known that I, MEYER ROSEN, a citizen of the United States, and a resident of Bloomington, in the county of McLean and State of Illinois, have invented an Improvement in Self-Lowering Journal-Jacks, of which the following description, in connection with the accompanying drawings, is a specification, like characters on the drawings representing like parts.

This invention relates to self-lowering journal jacks.

In order that the principle of the invention may be readily understood, I have disclosed a single embodiment thereof in the accompanying drawings, wherein—

Figure 1 is a transverse section taken through the jack;

Fig. 2 is a vertical transverse section upon the line 2—2 of Fig. 1;

Fig. 3 is a vertical transverse section upon the line 3—3 of Fig. 2;

Fig. 4 is a detail in section upon the line 4—4 of Fig. 1; and

Fig. 5 is a detail upon the line 5—5 of Fig. 1.

The jack, one embodiment whereof is shown in the accompanying drawings, is adapted for any use to which jacks are or may be applied, but particularly to lifting heavy loads, such for example as the driving wheels of engines. It may, however, be used in connection with automobiles and for numerous other purposes not necessary to enumerate.

Referring more particularly to the drawings, I have therein represented the casing of the jack as composed of inner and outer members 1, 2, the inner member 1 being preferably composed of a single cast part having a hollow base portion 3. Said member 1 in transverse section is rectangular, as clearly shown in Fig. 1, thus forming four vertical walls, 4, 5, 6, 7, all of which are continuous, with the exception of the wall 7 which, as shown at the left in Fig. 1, is formed with a vertical slot or opening to accommodate the thickened portion 8 of the adjacent wall of the member 2, said thickened portion 8 having integrally formed therewith teeth 9 in vertical alinement and constituting a rack. I provide suitable gearing, one member of which meshes with said rack, thereby to effect the lifting of the

member 2 of the casing. For this purpose I provide a shaft 10 having a squared outer end 11 to which a crank or other driving member may be applied. The shaft 10 which has a reduced inner end is mounted for rotation in a bearing 12 integral with which, as most clearly illustrated in Fig. 1, is a yoke 13 having opposite lugs 14, 15 respectively mounted in an inwardly extending web 16 of the wall 4, and the wall 6 of the inner member 1 of the casing. The shaft 10 extends through elongated slots 17, 18 of the casing members 1, 2, thus permitting rocking movement of the shaft 10 in a vertical plane about the lugs 14, 15 of the yoke 13 as pivots.

I provide the shaft 10 with a driving member that is adapted to be thrown into or out of gear with the parts to be driven by the swinging movement of the said shaft 10. For this purpose and in order to secure a relatively great leverage, I have secured upon the inner end of the shaft 10 a disk like member 19 having upon the inner face thereof a spiral cam 20 most clearly shown in Fig. 4. The adjacent ends 21, 22 of the spiral are spaced apart the distance of one tooth of the gear 23 fast upon the transverse shaft 24, whereby when the shaft 10 is in the position shown in Figs. 1 and 2, the rotation of said shaft effects the turning movement of the gear 23 and consequently of the shaft 24. The gear 23 is provided with teeth 24' which are shaped somewhat like those of a worm wheel; that is, they are substantially arc shaped.

Fast upon the shaft 24 which carries the gear 23 is a gear 25 meshing with a similar gear 26 upon the horizontal shaft 27, which has fast thereon a gear 28 meshing with the teeth 9 upon the inner face of the member 2 of the casing, whereby rotation of said shaft 10 through the gears 20, 23, 25, 26, 28 effects lifting movement of said member 2 of the casing.

The gear 25 upon the shaft 24 also meshes with and drives the gear 29 fast upon the shaft 30 extending transversely of the inner member 1 of the casing and mounted in the side walls thereof. Also fast on the shaft 30 is a gear 31 meshing with a gear 32 upon the horizontal shaft 33 likewise mounted in the inner member 1 of the casing. Thus, in the rotation of the shaft 10 in the elevation of

the member 2 of the casing, the gear 22 is rotated. Likewise fast upon the shaft 33 is a ratchet wheel 34 shown in side elevation in Fig. 5, and with which engage three pawls 35 pivoted at 36 upon a disk 37 loose upon the shaft 33, said pawls being held in contact with the teeth of the ratchet 34 by suitable springs 38. Surrounding the disk 37 is a brake band or strap composed of two members 39 pivoted at 39', and which have adjacent spaced ends or jaws 40 constituting substantially radially extending ears or lugs, from which laterally extend pins 41, surrounding which are coil springs 42, the outer ends of which bear against lugs or ears 43 formed with and inwardly extending from the wall 5 of the inner casing member 1.

When the shaft 10 is rotated in a direction to lift the outer casing member 2, the ratchet 34 is rotated in a counterclockwise direction, viewing Fig. 5, and the teeth thereof slide under the pawls 35. During such lifting movement of the outer member 2 of the casing, the members 39 constituting the brake band are pressed together by the coil springs 42, so as to hold the disk 37, and because of the engagement of the pawls 35 with the ratchet 34 prevents retrograde movement of said ratchet, and therefore of the shaft 33, and hence of the gear 28 and the rack 9.

Tapped into the wall 4 of the inner member 1 of the casing is a screw 44 having an operating handle 45, the outer member 2 of the casing being vertically slotted at 46 to permit the lifting movement of the outer member 2 of the casing. The said screw extends inwardly through the inner member 1 of the casing and has formed thereon two spaced collars 47 between which upon the stem of the screw 44 is mounted a yoke 48 which, as most clearly shown in Fig. 1, has laterally and inwardly extending therefrom an integral arm 49 terminating in a wedge 50 adapted to enter between the ends or jaws 40 of the brake band, and thereby to distend said brake band against the tension of the coil springs 42, and thus to release the disk 37. Connected to the yoke 48 at 51, as most clearly shown in Fig. 4, is an arm or link 52 that is connected to the yoke 13, the constriction being such that when the screw 44 is turned so as to move inward and force the wedge 50 between the jaws 40, thereby releasing the brake, the yoke 13 is rocked thereby, swinging the cam 20 out of mesh with the teeth of the gear 23.

It will be evident from the foregoing description that with the parts positioned as shown in Figs. 1 and 2, the jack is positioned beneath the part to be lifted, and by applying power to the shaft 10 the latter is rotated, and through the described gearing 23, 25, 26, 28 the outer member 2 of the casing 29 is lifted, and at the same time through the

gearings 23, 29, 31, 32 the ratchet 34 is rotated, the teeth thereof passing in a counterclockwise direction under the pawls 35. When it is desired to lower the jack, the screw 44 is turned in a direction to move the same inward, whereupon the wedge 50 spreads apart the members of the brake band 39, permitting the ratchet 34 to be turned in a clockwise direction under the stress of the load, thereby moving the disk 37 in the same direction because of the engagement of the pawls 35, and at the same time the cam 21 is swung outwardly from meshing relation with the gear 23.

The jack is thus very readily manipulated since by a slight movement of the screw 44 the parts are released, so that the outer member 2 of the casing slides down into the position shown in Figs. 2 and 3. Before again using the jack, the screw 44 is turned in the opposite direction so as to move it outwardly.

The outer member 2 of the casing is preferably provided with a handle 53 by which it may be lifted.

So far as I am aware, I am the first to employ a worm wheel or like part and a driving scroll therefor, as herein disclosed, and claim the same broadly, since it may be used not only in a lifting jack but as a mechanical movement in many different rela-

tions. Having thus described one illustrative embodiment of my invention, I desire it to be understood that although specific terms are employed, they are used in a generic and descriptive sense and not for purposes of limitation, the scope of the invention being set forth in the following claims.

Claims:

1. A jack comprising a casing composed of separable members, gearing for separating said members to effect the lifting movement and including a spiral cam and a gear wheel having arc-shaped teeth presenting substantially parallel faces respectively concaved and convex, a brake for said gearing, and means to disengage said gearing to permit return movement, said means being operatively connected to said brake.

2. A jack comprising a casing composed of separable members, gearing for separating said members to effect the lifting movement, a brake co-operating with said gearing, and means to disengage said gearing and release said brake.

3. A jack comprising a casing composed of separable members, gearing for separating said members to effect the lifting movement, and disengageable co-operating means including screw means to effect lowering of the jack.

4. A jack comprising a casing composed of separable members, gearing for separating said members to effect the lifting movement, and co-operating means including

screw means to effect disengagement of the gearing and return movement of the casing members.

5. A jack comprising a casing composed of separable members, gearing for separating said members to effect the lifting movement, and including a spiral cam, a gear wheel having arc-shaped teeth, each tooth having a concaved face, a brake for said gearing, and means operatively connected to said brake to move said cam out of meshing relation, thereby to effect return movement of the casing members.

10. A jack comprising a casing composed of separable members, gearing for separating said members to effect the lifting movement, said gearing including a ratchet, a surrounding member having pawls to engage said ratchet, a brake surrounding said members, and means to release said brake.

15. A jack comprising a casing composed of separable members, gearing for separating said members to effect the lifting movement and including means to prevent back movement of said gearing, and a screw to release said means preventing back movement of the gearing.

20. A jack comprising a casing composed of separable members, gearing for separating said members to effect the lifting movement and including a ratchet, a disk having pawls to engage said ratchet, a brake band to engage said disk, and a screw to release said brake band.

25. A jack comprising a casing composed of separable members, gearing for separating said members to effect the lifting movement and including a ratchet, a disk having pawls to engage said ratchet, a brake band to engage said disk, a screw to release said brake band, and means to disengage said gearing.

30. A jack comprising separable members, one of which is provided with a rack, gearing to separate said members including a gear constantly meshing with said rack, a driving member mounted for movement in and out of driving relation with said gearing and including a disk having one lateral face thereof formed as a spiral cam, and a gear wheel having arc shaped teeth engaging with said spiral cam and screw means to effect said movement in and out of driving relation.

35. A jack comprising separable members, one of which is provided with a rack, gearing to separate said members and including a gear constantly meshing with said rack, said gearing also including a disk-like member having on one face a spiral cam formation 20, a gear wheel having arc shaped teeth 24' engaging with said spiral cam, and presenting substantially parallel faces respectively concave and convex and means to swing said disk-like member into

and out of meshing relation with said gear wheel.

40. A jack composed of separable members, one of which is provided with a rack, gearing to separate said members and including a gear meshing with said rack, a driving member for said gear having swinging movement into active and non-active positions, and a screw for imparting such swinging movement to said driving member.

45. A jack having inner and outer casing members, the latter being provided with a rack, a train of gearing having a member meshing with said rack to lift the outer casing member, said gearing including separable members, and a screw carried with the casing and adapted to effect the separation of said members, thereby to permit self-lowering of the jack.

50. A jack having inner and outer casing members, the latter being provided with a rack, a train of gearing having a member constantly meshing with said rack to lift the outer casing member, said gearing including two separable gears, means carried by the casing to effect engagement and disengagement between said separable gears, thereby to effect self-lowering of the jack, and a brake operatively connected to said means to effect engagement and disengagement.

55. A jack comprising members 1, 2, the former having a rack 9, gearing including a gear constantly meshing with said rack and also including a cam 20, and screw means to disengage said cam from the gearing.

60. A jack comprising members 1, 2, the former having a rack 9, gearing meshing with said rack and including a cam 20, a movable member carrying said cam, and screw 44 operatively connected to said member and adapted to shift the same.

65. A jack comprising members 1, 2, the former having a rack 9, gearing meshing with said rack and including a cam 20, a ratchet 34 in driving relation with said gearing, pawls 35, a disk carrying said pawls, a brake to engage said disk and a member to effect disengagement of said cam 20 from the gearing and engagement of said brake with said disk.

70. A jack comprising members 1, 2, the former having a rack 9, gearing meshing with said rack and including a cam 20, a ratchet 34 in driving relation with said gearing, pawls 35, a disk carrying said pawls, and surrounding said ratchet, a brake surrounding and adapted to engage said disk, and means to release said brake.

75. A jack comprising members 1, 2, the former having a rack 9, gearing including a gear constantly meshing with said rack and also including a cam 20, a ratchet 34 in driving relation with said gearing, pawls 35, 130

a disk carrying said pawls, a brake to engage said disk, and means to release said brake and to disengage said cam 20 from the other members of the gearing.

5 20. A jack comprising a casing composed of separable members, gearing for separating said members to effect a lifting movement of one of said members, means to disengage said gearing to permit movement of the lifted member, a disk-like member driven by said gearing, a brake about said disk-like member, and means to move the brake into braking relation with said disk-like member only upon engagement of said gearing to permit said lifting movement.

21. A jack comprising a casing composed of separable members, gearing for separating said members to effect the lifting movement, a ratchet driven from said gearing, a member having pawls to engage said ratchet, a plural member brake to engage said pawl member, and means acting to dis-

engage the gearing and to expand the members of said brake.

25

22. A jack comprising a casing composed of separable members, gearing for separating said members for effecting the lifting movement, means to disengage said gearing to permit return movement, a brake for said gearing, and a member to effect disengagement of said gearing and operative engagement with said brake.

30

23. A jack comprising a casing composed of separable members, gearing for separating said members for effecting the lifting movement, means to disengage said gearing to permit return movement, a brake for said gearing, and a member operatively related to said brake and gearing and adapted to effect disengagement of the gearing with engagement of the brake, and vice versa.

35

In testimony whereof I have signed my name to this specification.

MEYER ROSEN.
